HOLDER FOR CHARACTER-CARRYING ELEMENTS FOR COMPOSING MACHINES

Frederick F. Simmons, Merriam, Kans.

Application February 23, 1949, Serial No. 77,945

2 Claims. (Cl. 294—67)

1

My invention relates to character-carrying elements for composing machines. More particularly, my invention relates to a holder for a plurality of such elements whereby they may be simultaneously treated to provide a dark background for the identifying symbol for each element, whereby to achieve a structure analogous to that disclosed in the patent to Percy L. Hill, dated March 10, 1931, Patent No. 1,796,023. The character-carrying elements aforesaid may be treated in a variety of ways for achieving a dark-background for the individual identifying symbols, and it is obviously advantageous to treat a plurality of such elements simultaneously to provide such a background.

With the foregoing in view, it is an object of my invention to provide an improved holder and/or carrier for holding a plurality of character-carrying elements for simultaneous treatment to provide such a dark or contrasting background for the identifying symbols thereof.

A further object is to provide a holder for the purpose aforesaid which comprises a hollow container having an open bottom but being closed at the sides, ends and top, said container including means for clamping a plurality of character-carrying elements therein in face-to-face relation, the portions of said elements to be colored being exposed to said open bottom of said container, and means for detachably connecting a carrying handle to said container for carrying the same with the top wall thereof uppermost.

A further object is to provide in a container such as that last described a strip for partially closing said open bottom of said container, and means for rigidly and readily detachably connecting said strip across said open bottom of said container to partially close the same.

Other objects and advantages reside in the particular structure of the invention, the structure of the several elements thereof, combinations and sub-combinations of such elements, all of which will be readily apparent to those skilled in the art upon reference to the attached drawing in connection with the following specification, wherein the invention is shown, described and claimed.

In the drawing:

Figure 1 is a plan view of the device according to the invention, a portion of the carrying handle being broken away;

Figure 2 is a side elevational view thereof;

Figure 3 is a bottom plan view thereof;

Figure 4 is an end elevational view looking from the right of Figure 2;

2

Figure 5 is a fragmentary perspective view of the invention;

Figure 6 is a perspective view of one of the character-carrying elements adapted to be carried by the holder according to the invention.

Referring specifically to the drawing, wherein like reference characters have been used throughout the several views to designate like parts, and referring at first to Figures 5 and 6, 10 designates generally one or more character-carrying elements with which the holder according to the invention is adapted to be utilized. Thus, the character-carrying element 10 is adapted to be used with a composing machine, such as a 15 Linotype machine, for the formation of lines of type. Thus, one edge of each element 10 may be formed with a recess 11 formed with a matrix for casting a character, such as the letter "H." An opposite edge of such element 10 is customarily 20 impressed with a like character 13 for identifying the particular matrix 11. As taught in such patent aforesaid, the impressed character 13 is hard to see with the naked eye, whereby the edge 12 of the element is colored a contrasting color 25 and the identifying symbol 13 is thereafter likewise colored with a different contrasting color, so as to cause the symbol 13 to stand out. As so far described, the structure is conventional and forms no part of my invention.

However, the edge surface 12 may be darkened in a number of ways and by a number of processes or methods. None of such processes or methods forms any particular part of this invention, but the device of the invention is capable of being used for simultaneously coloring the edge surfaces 12 of a plurality of elements 10 simultaneously by a wide variety of processes and/or methods.

Referring now to Figures 1 to 5, inclusive, the holder according to the invention comprises a hollow rectangular container generally indicated at 14 and which includes imperforate top wall 15, a pair of impervious opposed side walls 16, and a pair of imperforate opposed end walls 17 and 18 which, as shown, are preferably substantially thicker than the side and top walls aforesaid. The end wall 18 is formed with an internally-threaded bore 19 therethrough in which is rotatably supported a longitudinally extending holding element or screw 20, the free inner end of which is adapted to extend inwardly of the container 14 to clampingly engage a plurality of character-carrying elements 10 so as to clamp the same in the container with the edges 12 exposed through the open bottom of the container.

The outer end of the screw 20 projects beyond the end wall 18, the projecting end being provided with a hand actuatable means 20'. As clearly seen in Figure 5, the interior dimensions of the container 14 are such as to have a close fit with a plurality of such elements 10 when the same are clamped therein in face-to-face relation.

When the container 14 is filled with a plurality of elements 10, it is obvious substantially heavy, whereby I have provided means for conveniently transporting the same from place to place. Preferably, the end walls 17 and 18 are formed with means adapted for readily detachably engaging the carrying handle spanning the top wall 15 in upwardly-spaced relation thereto, whereby the container may be transported with the top wall 15 uppermost. In the embodiment illustrated, the end walls 17 and 18 are each formed with an upwardly-directed extension 21 or 22, each of which is formed with an aligned aperture 23. In effect, the extensions 21 and 22 provide bail ears. A carrying handle now to be described is adapted to be readily detachably connected to the bail-ear-providing extensions 21 and 22.

In the embodiment illustrated, the carrying handle comprises an elongated straight rod 24 which is slidably and pivotally seated in the aligned apertures 23 so as to provide opposite ends extending oppositely outwardly of the end walls 17 and 18. The rod 24 has a free end 25. The other end of the rod 24 is preferably upwardly directed, as at 26, and then reversely directed to provide an upper rod handle 27 extending lengthwise of the top wall 15 of the container in upwardly-spaced relation thereto. The rod 27 comprises the carrying handle or bail for the device. The handle portion 27 has a free end which is downwardly directed, as at 28, and terminates in an upwardly-directed hook 29 adapted to be detachably engaged with the free end 25 of the rod 24 to anchor the free end of the handle 27.

As so far described, it is obvious that the holder provides a convenient holder and/or carrier for a plurality of the character-carrying elements 10, wherein the edge surfaces 12 are exposed for treatment. Thus, in some methods or processes for coloring or darkening the edges 12, it is desirable to buff or otherwise clean such surfaces prior to treatment. With the surfaces 12 exposed through the open bottom of the container, it is a simple matter to buff or clean a large number of such surfaces substantially simultaneously. Likewise, where the coloring or darkening processes used embody coating or dipping of such surfaces 12 with or in chemical solutions, the particular container or carrier is adapted for this purpose. Thus, if the coloring is to be accomplished by coating, the container may be readily turned on its side, or stood on one end, while the coating step is being carried out. Likewise, if the process involves dipping in a container of chemicals, it is a simple matter to simply set the container with the open bottom downward in the pan or other chemical container. Where the pan is shallow, the top of the container and the carrying handle 27 are exposed, whereby the device may be readily placed therein and removed therefrom. However, at times, it may be desirable to partially close the open bottom of the container. Also, in certain processes for coating the surfaces 12, it may be necessary to plate such surfaces with copper or other metal and in such processes it is desirable to locate a strip of material utilized in the plating steps in near-adjacent relation to

the surfaces 12. Thus, in copper plating by electricity, it would be desirable to mount the electrode of plating material closely adjacent the surfaces 12. Likewise, in non-electrical plating methods, it may be desirable to mount a metallic strip, not necessarily of plating material, in a similar position.

With the foregoing in view, means have been provided for mounting a strip of material across the open bottom of the container so as to partially close the same and locate the strip in adjacent relation to the surfaces 12 of the elements in the container. Such a strip is indicated at 30 and is adapted to span the open bottom and to be connected to the bottom edges of the end walls 17 and 18 between the side walls 16 of the container. The ends of the strip 30 may be connected to the bottom edges of the end walls 17 and 18 in any suitable manner, but in the embodiment illustrated, the ends of the strip are formed with keyhole slots 31 which are adapted to be readily detachably engaged with headed studs 32 fixed to the bottom edges of the end walls 17 and 18. Thus, it is apparent that a strip 30 of any suitable material, whether used as a partial closure for the bottom, or as means for assisting in a coating step for the edges 12, is readily securable across the open bottom and may be quickly attached to and/or removed therefrom.

While I have shown and described what is now thought to be a preferred embodiment of the invention, it is obvious that the same is susceptible of other forms and expressions. Consequently, I do not limit myself to the precise structures shown and described hereinabove except as hereinafter claimed.

I claim:

1. In a holder for a plurality of character elements for a composing machine, an elongated open bottom container having laterally spaced side walls, end walls secured to and extending between the ends of the side walls, and a top wall extending between and secured to the upper ends of the side walls and end walls, the character elements being adapted to be positioned transversely between the side walls in sidewise engagement with each other and with one of said end walls, means extending longitudinally between the other end wall and the adjacent character element and arranged to hold the elements in sidewise engagement with each other and said one end wall, a longitudinally elongated strip narrower than said container and extending along the open bottom of the container for engaging limited portions of the bottom edges of the character elements for holding the same in place in the container, said strip being laterally spaced from the side walls, the bottom ends of said end walls having means detachably engageable with end portions of said strip for mounting the strip in place against the bottom ends of said side walls.

2. In a holder for a plurality of character elements for a composing machine, an elongated open bottom container having laterally spaced side walls, end walls secured to and extending between the ends of the side walls, and a top wall extending between and secured to the upper ends of the side walls and end walls, the character elements being adapted to be positioned transversely between the side walls in sidewise engagement with each other and with one of said end walls, means extending longitudinally between the other end wall and the adjacent char-

acter element and arranged to hold the elements in sidewise engagement with each other and said one end wall, a longitudinally elongated strip narrower than said container and extending along the open bottom of the container for engaging limited portions of the bottom edges of the character elements for holding the same in place in the container, said strip being laterally spaced from the side walls, the bottom ends of said end walls having means detachably engageable with end portions of said strip for mounting the strip in place against the bottom ends of said side walls, and a handle including a rod extending along and spaced above the top wall and having end portions connected to said end walls for carrying the container with its open bottom facing downwardly.

15 FREDERICK F. SIMMONS.
